(57) **CLAIM**

The ornamental design for an electrocardiograph cable, as shown and described.

DESCRIPTION

FIG. 1 is a front elevational view of a first embodiment of an electrocardiograph cable showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front and right side perspective view thereof;

FIG. 8 is a bottom, rear and left side perspective view thereof;

FIG. 9 is a rear and left side perspective view thereof;

FIG. 10 is a top, front and left side perspective view thereof;

FIG. 11 is a bottom, front and right side perspective view thereof;

FIG. 12 is a front elevational view of a second embodiment of the electrocardiograph cable showing our new design;

FIG. 13 is a rear elevational view of FIG. 12;

FIG. 14 is a left side view of FIG. 12;

FIG. 15 is a right side view of FIG. 12;

FIG. 16 is a top plan view of FIG. 12;

FIG. 17 is a bottom plan view of FIG. 12;

FIG. 18 is a front and right side perspective view of FIG. 12;

FIG. 19 is a bottom, rear and left side perspective view of FIG. 12;
